COUPLING MEANS FOR CABLES

William A. Bruno, Astoria, N. Y., assignor, by
mesne assignments, to Bruno Patents Inc.,
Long Island City, N. Y., a corporation of New
York

Application June 10, 1941, Serial No. 397,355

2 Claims. (Cl. 174—22)

This invention relates to connectors or coupling means for single conductor shielded cables, and more particularly to connectors for co-axial cables.

The main object of my invention is to provide friction and constriction electrical contacts, and to produce particularly safe and stable electrical connections between the conductors of the cables.

It is also an object of my invention to provide coupling accessories for co-axial cables, which can be easily and quickly connected and disconnected, and are capable of providing electrical and gaseous connections in the cable thereby rendering all electrical connections air-tight.

A further object of my invention is to provide a connector element for shielded cables, which can be easily fastened on the cable, and which simultaneously forms electrical connection with the outer conductor.

Other objects and advantages will become apparent from the specification, taken in connection with the accompanying drawing, in which

Fig. 1 is a sectional view of one embodiment of my invention illustrating a first connector member fastened at the end of a co-axial cable, assembled with a second connector member, the latter being partly broken away;

Fig. 2 is a sectional view of the second connector member shown in Fig. 1 partly broken away, and

Fig. 3 is a diagrammatical illustration of the principle used in my invention.

Referring to Fig. 1, the co-axial cable 1 shown therein in section, may be of the solid copper tubing type, the braided type or any other form of shielded conductor cable. 2 is the center conductor of the cable; 3, 3' are spacing insulating washers; 4 is the barrel of the connector proper; 5 is the locking nut, and 6 is the insulating washer of the connector. A contact member 7, to which the center conductor 2 of the cable 1 is electrically connected by soldering, for example, extends through said insulating washer 6. Once washer 6 is screwed into place, an eyelet 8 makes contact with the outer conductor 10 of the co-axial cable. The connector barrel 4 may have a slotted tubular extension 11 which fits into a corresponding annular recess 15 of the receptacle type connector element shown in Figs. 1 and 2. An air-tight joint may be produced by means of a rubber gasket 9, once the nut 5 is screwed over the corresponding connector part.

In order to connect the connector of the male plug type shown in Fig. 1 to an end of a co-axial cable, it is necessary to remove the cotton 55

braid cover, if this is present, for about $\frac{1}{8}$ " from the end, for example, thus exposing the conductor braid or solid copper tubing which forms the outer conductor of the cable. The center conductor tube is cut so as to protrude about $\frac{1}{2}$ " from the extremity of the cable. Barrel 4 is now made to slide over the end of the cable 1 to which the connector is to be fastened, far enough to allow the exposed outer conductor to protrude just beyond the smaller diameter hole in the connector barrel 4. When this has been done, eyelet 8 is inserted over the braid, and insulating washer 6 is screwed into barrel 4, taking care to allow the center conductor to pass through contact member 7. By screwing the insulating washer 6 into place, eyelet 8 will force the outer conductor 10 against the surface of connector barrel 4, thus forming a good electrical contact.

As further precaution against gas leak, the cable may be introduced into a metal tube 31, if desired, and a tight connection between the end of said metal tube and the barrel may be secured by using conventional coupling means 32, as shown.

The receptacle type connector shown in Figs. 1 and 2 consists of a metallic barrel 12 having a suitable recess to accommodate an insulating washer, such as shown at 13, through which the slotted center contact pin 14 extends. This contact pin has a recess 33 and receives contact member 7 when the two connector parts are assembled, as shown in Fig. 1. According to my invention, the conical portion 42 of pin 33 is constricted around the cylindrical portion of pin 7 when the assembly clamping nut is tightened, and this constriction contact is supplemented by friction contact along the shank of the pin. Barrel 12 may be provided with an annular recess 15, which receives the slotted tubular extension 11 of the male plug type connector part, whereby proper electrical contact between the outer conductor and barrel 12 is secured, even without tightening locking nut 5.

Once the extension connector shown in Fig. 2 is connected with the male type connector of Fig. 1 and locked by nut 5, a safe contact is established between the contact piece 7 and center conductor pin 14, as well as between the outer cable connector 10 and barrel 12 of the extension connector, while rubber gasket 9 is compressed by the face of the extension connector barrel 12, producing a tight gas seal.

It is to be understood that my invention is not limited to the specific embodiments presented

herein for illustration, and is susceptible of modifications within the scope of the invention as defined in the appended claims.

I claim:

1. In a coupling means for electrically connecting cables, contact means comprising a slotted, cylindrical, female contact pin provided with a conical end portion at its outer end, and a recess adapted to receive a registering, cylindrical male contact pin; a cylindrical male contact pin provided with a shoulder having a conical recess registering with said conical end portion of said female contact pin, and locking means for causing tight electrical engagement of said slotted, cylindrical, female contact pin, and said cylindrical male contact pin by constriction contact and friction contact.
2. In a coupling means for electrically connecting co-axial cables, said coupling means com-

prising a connector element of the receptacle type, and a connector element of the male plug type; said connector element of the receptacle type being provided with a slotted, cylindrical, female contact pin provided with a conical end portion at its outer end, and a recess adapted to receive a cylindrical male contact pin; said connector element of the male plug type comprising a cylindrical male contact pin provided with a shoulder having a conical recess registering with said conical portion of said female contact pin of said connector element of the receptacle type, and locking means for causing tight electrical engagement of said slotted, cylindrical female contact pin and said cylindrical male contact pin by constriction and friction contact, for electrically connecting the central conductors.

WILLIAM A. BRUNO.
